TAKE-OFF MECHANISM FOR MATCH MACHINES

Franklin Moore, Oshkosh, Wis.

Application May 25, 1937, Serial No. 144,583

8 Claims. (Cl. 144—50)

This invention relates to continuous match making machines and more particularly to improved match take-off mechanism for use in connection therewith.

5 The principal object of the invention is to provide simple and efficient mechanism whereby the matches as they are rapidly discharged row by row from the carrier of a match machine are progressively deposited and arranged within the 10 take-off trough in superposed substantially parallel rows and at the same time are advanced, in bulk, in an orderly manner to the delivery portion of the trough.

With this object in view, and others which 15 will appear, my invention comprises novel features of construction and combinations of parts which in a preferred form will be hereinafter described; the scope of the invention being expressed in the appended claims.

20 In the drawings—

Figure 1 is an elevation partly in section of a form of take-off mechanism embodying my invention, showing the relation of the mechanism to the discharge station of a match machine.

25 Fig. 2 is a plan of the mechanism shown in Fig. 1.

Fig. 3 is a longitudinal vertical section through the match trough, as on the line 3—3 of Fig. 2.

Fig. 4 is a transverse vertical section, as on 30 the line 4—4 of Fig. 1.

Fig. 5 is a transverse vertical section of portions of the trough and match carrier, showing a part of the punch head for ejecting the succeeding rows of matches from the carrier and indicating the action of a row of matches in the carrier upon the matches in the trough as such row approaches the punch-out level.

Figs. 6 and 7 are similar sections through the trough and adjuncts, as on the lines 6—6 and 40 7—7, respectively, of Fig. 1.

Fig. 8 is a sectional perspective of the trough and take-off mechanism.

Referring to the drawings, 10 designates a portion of the delivery end of the travelling carrier of a continuous match making machine, which carrier in the form illustrated comprises a multiplicity of suitably perforated plates linked together in endless series; 11 designates a horizontal row of reciprocating spaced punches by means of which the completed matches are ejected row by row from the plates during the progression of the carrier, and 12 designates a vibratable take-off trough extending transversely of the carrier and below the level of the punches, which trough receives the discharged matches in

substantial parallelism and advances them therealong in an orderly manner to the delivery end of the trough, thence discharging the matches into a packing or box filling apparatus. The trough, which rests upon basal supports 13, 5 is rapidly vibrated by any suitable means, that shown comprising the usual adjustable eccentric and slide block connection whereof the eccentric 14 is mounted on a power driven shaft 15.

According to the principle of my invention the 10 matches which are delivered to and contained in the portion of the trough that is located at and transversely of the match carrier are yieldingly supported in such manner that the uppermost row of matches are at or in close proximity to 15 the punch out level to the end that each succeeding row of matches is ejected from the carrier directly against and is sustained by such upper row, thus insuring minimum disarrangement of the matches in the trough. In the 20 construction illustrated the yielding match support within the trough is constituted by a vertically resilient longitudinally extending bed which inclines downwardly from the receiving to the discharging end of the trough, or substantially so. This bed comprises upper and lower 25 end sections 16 and 17, respectively, and a longer connecting section 18 therebetween, the whole presenting a substantially uninterrupted upper surface for the support of the matches. The 30 section 16 at the higher end of the bed constitutes, in effect, a lever which is composed of a relatively short normally inclined plate whereof the lower end is fastened to a transverse rock-shaft 19 having its bearings in the side walls of 35 the trough, and whereof the higher end is provided adjacent the outer or right-hand edge of the match carrier with an upstanding leg 20 terminating in an angular arm 21. This arm 21 is resiliently supported in any suitable manner 40 in order to maintain the adjacent end of the lever section 16 relatively near to the punch-out level of the match machine, such supporting means in the present instance consisting of a tension spring 22 which depends from a suitably 45 located fixture on the frame of the machine, and which spring is attached at its lower end to the arm 21. The upper end of the intermediate section 18 is loosely supported by the rock-shaft 19, and its lower end has spliced thereto 50 the section 17, which latter section is preferably of spring metal and has its free end resting upon the floor of the trough.

One end of the rock-shaft 19 has fixed thereto an upstanding arm 23 which is pivotally con- 55

nected by means of a link 24 to a crank-arm 25 fast on a rock-shaft 26 which is journaled in a pair of up-standing arms 27 that are secured to the side walls of the trough adjacent its delivery 5 end. Hence if the shaft 19 be oscillated, by vertical actuation of the lever section 16, the motion will be transmitted to the shaft 26, as will presently appear. The latter shaft has fastened thereto a clamp member 270 to which is secured 10 the inner or upper end of a longitudinal rod 28 which centrally overhangs the lower plate section 17 and normally inclines downwardly to and upon such section, and which rod partakes of the arcuate movement imparted to the shaft 26 15 through its crank and link connection with the shaft 19. This rod 28 constitutes an egress governing means for the matches at the delivery end of the trough. Loose on the shaft 26 are two pendant plates 29 which flank the clamp member 270 and which plates support between them the lower end of a central rod 30 that inclines upwardly to a position in proximity to the match carrier, terminating in an upwardly curved portion 31 which is supported and guided in the 20 slotted curved foot 32 of an angulated fixture 33. This fixture is adjustably fastened to a bracket 34 which is bolted to the machine frame adjacent the match carrier. The upper portion of the rod 30 extends freely through the perforated head 35 of a set-screw 36 which is threaded in the cross-bar 37 of a saddle member, whereof the legs are suitably attached to the respective sides of the trough, as at 38. It will 25 be seen that by longitudinally adjusting the set-screw 36 in its support the upper end of the rod 30 can be raised and lowered to regulate the space between such rod and the plate section 17, thus providing a throat of determined size for the passage of matches to the delivery end of the 30 trough.

The upper or right hand end of the lever section 16 has secured thereto adjacent the perforated area of the carrier the foot of an up-standing spring plate 39 which slidably bears 35 against a fixture 40 which is supported similarly to the fixture 33 at the left-hand side of the carrier, thus providing a vertical end wall or barrier for the matches imposed on the section 16 irrespective of the varying angularity of the 40 latter. (See Figs. 1 and 3.)

The operation of the foregoing described mechanism may be briefly stated as follows, it being understood that normally the lever section 16 of the match supporting bed within the 45 trough is maintained by the spring 22 in raised position as seen in Fig. 1. During the operation of the match machine the trough 12 is rapidly vibrated by the action thereon of the eccentric and block connection, and at the same time 50 the punches 11 rapidly eject the matches row by row from the travelling match carrier, the matches thus discharged entering the take-off trough and dropping upon the inclined supporting bed. The punches are carried by the usual 55 cam-operated reciprocating punch head. The bodily vibration of the trough causes the matches therein to roll down the inclined bed and against the opposing egress rod 28, which rod at this juncture is in down or closing position at the 60 delivery end of the trough. The continued vibration of the trough causes the succeeding rows of matches which are discharged from the carrier and deposited in the trough to crowd down in bulk until the match level within the trough 65 in the region of the match carrier is raised to

or about the level of the punches, whereupon downward pressure is exerted on the opposing upper matches in the trough by the advancement of the carrier to present a new row of matches to the path of the punches. As the flow 5 of matches down the inclined bed has been checked by the egress rod 28, the downward pressure of each succeeding row of matches borne by the carrier increases and progressively overcomes the tension of the spring 22 until the upper end of the lever section 16 is depressed, as seen in Fig. 3. The matches on being expelled from the carrier by the punches, do not hit the ends of the matches previously positioned on the lever 16, because each succeeding row of downwardly moving matches, endwise held in the carrier, impinges upon and presses down the opposing matches thus positioned before each row is expelled by the punches. Since the inner end of this section 16 is secured to the shaft 19, 20 a slight clockwise motion of the shaft is effected, thus by virtue of the link and crank connection producing a corresponding movement of the arm 25, the link 24 being drawn to the right and the arm 25 and its shaft 26 being moved therewith. 25 Such movement of the arm 25 gradually raises the egress rod 28 as the matches pass thereunder, thus permitting the matches in increasing quantities to escape from the trough till the rod 28 reaches its fully open position in substantial 30 parallelism with the spring plate section 17, which condition obtains during the ensuing operation of the match machine.

If during the operation of the machine the downward pressure of the matches on the supporting bed should become too great to be controlled by the spring sustained lever section 16, the pitch of the bed will be increased by virtue of the resulting depression of a greater length of the resilient end section 17. This will greatly 40 enlarge the exit passage constituted by the space between the section 17 and the overhanging rod 28, thus allowing a quick escape of surplus matches, whereupon the bed will automatically resume its normal operating pitch. 45

It will be seen that the matches contained in the vibrating trough are held in closely packed relation by the conjoint action of the yielding supporting bed, its spring loaded lever section, the throat rod, and the egress governing member 50 under the control of the section, and that such matches are maintained at "punch out" level. Hence practically all the matches which are discharged from the carrier lie in parallelism within the trough, thus reducing the spill heretofore 55 occasioned by crossed splints.

It will also be seen that the movement of the lever section 16 in opposition to the action of the spring 22 is efficiently attained by the downward pressure of each succeeding row of supported matches in the match carrier as such row approaches and reaches the punch out level, thus ensuring a practically constant but light upward pressure of the lever section and the mass of matches superposed thereon; that each row of 65 matches being punched out of the carrier is held between the next following row in the carrier and the top row in the trough, so that in their discharge from the carrier very few matches may be disarranged or driven hard 70 against the outer wall of the trough, and that by virtue of the contact of the rigidly held matches in the carrier with the uppermost matches in the vibrating trough, the latter matches are rotated so as to remove the fuzz from the splints and 75

polish them, it being noted that by varying the tension of the spring 22 on the lever section 16 and the vibratory frequency of the trough, varying polishing results may be effected. Furthermore, by virtue of the capacity for the adjustment of the relative pitch of the trough and the vibration thereof, there is obviated the use of the usual partition carrying take-off chain with its attendant liability to disarrange the matches in the trough when the partitions in their return travel from the matches are leaving the trough. It is to be understood that the invention is not limited to the particular exemplifying form thereof herein disclosed, as the mechanism may be modified within the principle of the invention and the scope of the appended claims.

I claim—

1. In take-off mechanism for a match machine having a travelling carrier for succeeding parallel rows of matches, and means for discharging the matches horizontally row by row from said carrier, a vibrating match-receiving trough extending transversely of the carrier, a member normally inclined within and longitudinally of the receiving end of the trough, resilient means for retaining the upper end of said member elevated to maintain said member in inclined position, means connecting the lower portion of said member to the trough whereby said member has capacity for vertical movement in a path below the match discharge level, and whereby as the rows of matches are moved in succession to the action of the said discharging means such matches exert downward pressure upon the preceding uppermost rows on said member, thus progressively depressing the underlying matches and said member, egress governing means for the delivery end of the trough, said governing means supported by the trough, and operative connection between said governing means and said member.

2. In take-off mechanism for a match machine having a travelling carrier for succeeding parallel rows of matches, and means for discharging the matches horizontally row by row from said carrier, a vibrating match-receiving trough extending transversely of the carrier, a member normally inclined within and longitudinally of the receiving end of the trough, resilient means for retaining the upper end of said member elevated to maintain said member in inclined position, means connecting the lower portion of said member to the trough whereby said member has capacity for vertical movement in a path below the match discharge level, and whereby as the rows of matches are moved in succession to the action of the said discharging means such matches exert downward pressure upon the preceding uppermost rows on said member, thus progressively depressing the underlying matches and said member, egress governing means for the delivery end of the trough, said governing means supported by the trough, operative connection between said governing means and said member, a throat member pivotally connected to the trough adjacent to the said governing means, and means for vertically adjusting said throat member in relation to the trough.

3. In take-off mechanism for a match machine having a travelling carrier for succeeding parallel rows of matches, and means for discharging the matches horizontally row by row from said carrier, a vibrating match-receiving trough extending transversely of the carrier, a match supporting element normally inclined within and

longitudinally of said trough and effective to feed the matches from the receiving to the delivery end of the trough, said element including an upper section within the receiving end of the trough, a connection between the inner end of said section and the trough and a spring connection between the opposite end of said section and the trough, whereby said section has capacity for vertical movement in a path below the match discharge level, egress governing means for the delivery end of the trough, said governing means supported by the trough, and operative connection between said governing means and said upper section.

4. In take-off mechanism for a match machine having a travelling carrier for succeeding parallel rows of matches, and means for discharging the matches horizontally row by row from said carrier, a vibrating match-receiving trough extending transversely of the carrier, a normally inclined match supporting element mounted within and longitudinally of said trough and effective to feed the matches from the receiving to the delivery end of the trough, a connection between the trough and said supporting element, said element comprising a series of sections including an upper section arranged to support at the receiving end of the trough each succeeding uppermost row of the matches delivered to the trough, a resilient lower section resting on the floor of the trough, and an intermediate connecting section, the whole presenting an uninterrupted inclined match supporting surface, a spring normally sustaining said upper section in such position that the uppermost matches thereon lie substantially at the discharge level of the match machine, whereby as the rows of matches borne by the carrier move in succession to the action of the discharging means such matches exert downward pressure upon the preceding uppermost rows in the trough and thereby progressively depress the underlying matches and the spring sustained supporting section therefor, egress governing means for the delivery end of the trough, said governing means supported by the trough, and operative connection between said governing means and said upper section at the point of said connection between the trough and the element.

5. In take-off mechanism for a match machine having a travelling carrier for succeeding parallel rows of matches, and means for discharging the matches horizontally row by row from said carrier, a vibrating match-receiving trough extending transversely of the carrier, a normally inclined match supporting element mounted within and longitudinally of said trough and including an upper control section pivotally supported by the receiving end of the trough, a spring tending normally to maintain said section in raised position and with the uppermost matches thereon located at a level substantially at the discharge level of the match machine, egress governing means for the delivery end of the trough, said governing means supported by the trough, and operative connection between said governing means and the said control section.

6. In take-off mechanism for a match machine having a travelling carrier for succeeding parallel rows of matches, and means for discharging the matches horizontally row by row from said carrier, a vibrating match-receiving trough extending transversely of the carrier, a normally inclined element supported by and mounted within and longitudinally of said trough and in-

- cluding an upper control section pivotally supported at the receiving end of the trough, a spring in cooperating relation to the upper end of said control section and tending normally to maintain said section in raised position and with the uppermost matches on said section located at a level substantially at the discharge level of the match machine, a throat member connected to said trough and overhanging the lower portion of said element, an egress governing member also overhanging said element below the throat member, said governing member supported by the trough, and operative connection between said governing member and the said control section.
7. In take-off mechanism for a match machine having a travelling carrier for succeeding parallel rows of matches, and means for discharging the matches horizontally row by row from said carrier; a vibrating match-receiving trough extending transversely of the carrier, a normally inclined match supporting element mounted within and longitudinally of the trough and including an upper control member at the receiving end of the trough, a rock-shaft to which the lower portion of said control member is secured, said shaft supported by the trough, a spring in cooperating relation to the upper portion of said control member and tending to maintain said section normally in raised position and with the uppermost matches on said section located substantially at the discharge level of the match machine, a throat member overhanging the lower portion of said element, an egress governing member also overhanging said element below the

throat member, a rock-shaft mounted on the trough and supporting said egress member, and a crank and link connection between the two rock-shafts.

8. In take-off mechanism for a match machine having a travelling carrier for succeeding parallel rows of matches, and means for discharging the matches horizontally row by row from said carrier, a vibrating match-receiving trough extending transversely of the carrier, and a normally inclined match supporting element mounted within and longitudinally of said trough, said element comprising a series of sections including an upper section arranged to support at the receiving end of the trough each succeeding uppermost row of matches delivered to the trough, a lower spring section resting on the floor of the trough and an intermediate connecting section, a rock-shaft to which the lower end of the upper section is secured and upon which shaft the upper end of the intermediate section is loosely supported, said rock shaft supported by the trough, a spring in cooperating relation to the upper portion of said upper section and tending to maintain said upper section normally in raised position and with the uppermost matches on said upper section located substantially at the discharge level of the match machine, a throat member overhanging the lower portion of said intermediate section, an egress governing member overhanging the lower spring section, said governing member supported by the trough, and operative connection between said governing member and the said upper section.

FRANKLIN MOORE. 35
